ELECTRIC MOTOR

William A. Rutledge and Stanley L. Lindt, Fort Wayne, Ind., assignors to General Electric Company, a corporation of New York

Filed June 20, 1962, Ser. No. 70,629

Term of patent 14 years

(Cl. D26—5)

Fig. 2.

Fig. 3.

Fig. 4.

Fig. 5.

Fig. 1.

FIG. 1 is a perspective view of an electric motor employing the new design;

FIG. 2 is a front elevational view as seen from the right of FIG. 1;

FIG. 3 is a rear elevational view as seen from the left of FIG. 1;

FIG. 4 is an elevational view as seen from the bottom of FIG. 1; and

FIG. 5 is an end elevational view of the motor in FIG. 1.

The dominant features of the design reside in the portions as shown in full lines.

We claim:

The ornamental design for an electric motor, as substantially shown and described.
